COLLAPSIBLE BUILDING

David D. Arehart and Ralph T. Dittmer, Flint,
Mich., assignors to Palace Corporation, Flint,
Mich., a corporation of Michigan

Application September 20, 1946, Serial No. 698,147

4 Claims. (Cl. 189—2)

1

This invention relates to a new and improved collapsible building structure and more particularly to a structure of this character adapted to be erected and dismantled with a minimum of labor in a short space of time.

It is an object of the present invention to provide a building structure comprising a plurality of similar units which may be associated to form buildings of various sizes as desired.

It is also an object to provide units for such a building, which units are collapsible to form compact folded books or packages containing the various elements of the unit.

It is an additional object to provide a structure which may be formed mainly or entirely of metal and which is durable and will withstand repeated erection and dismantling without injury to the parts.

It is a further object of our invention to provide a collapsible roof structure in which the roof elements and the supporting girder members are permanently connected, the truss members folding within the roof elements for shipment.

It is another object to provide a structure in which roof supporting and wall elements are detachably secured to the roof structure and may be housed within the folded roof structure for shipment.

It is also an object to provide a structure which is rigidly braced and adapted to sustain substantial roof loads and high wind pressures.

It is an additional object to provide a building structure which may include floor elements adapted to serve as housings for the other elements when packed for shipment.

Other and further objects will appear as the description proceeds.

We have shown certain preferred embodiments of our invention in the accompanying drawings, in which—

Figure 1 is a plan view of a two unit assembly;

Figure 2 is an end view of the structure of Figure 1;

Figure 3 is a side view of the construction of Figure 1, a third element being partially shown;

Figure 4 is a fragmentary section, on an enlarged scale, showing the hinge and ridge construction, the folded position being indicated in broken lines;

Figure 5 is a view similar to Figure 4 showing the ridge securing and raising devices;

Figure 6 is a side view of the construction of Figure 5, showing a plurality of securing units on a reduced scale;

Figure 7 is a section taken on line 7—7 of Figure 6;

2

Figure 8 is a fragmentary side elevation of one form of construction for connecting the roof girders and supporting posts;

Figure 9 is a section taken on line 9—9 of Figure 8;

Figure 10 is a section taken on line 10—10 of Figure 8;

Figure 11 is a fragmentary section taken on line 11—11 of Figure 8;

Figure 12 is a fragmentary section taken on line 12—12 of Figure 8;

Figure 13 is a view similar to Figure 8 showing a modified form of construction;

Figure 14 is a section taken on line 14—14 of Figure 13;

Figure 15 is a view, partly in section, taken on line 15—15 of Figure 13;

Figure 16 is a fragmentary section showing the lateral interlock of adjacent roof sections;

Figure 17 is a fragmentary section showing the means for supporting adjustable upper wall sections or vent flaps on the posts;

Figure 18 is a face view of an upper wall section and its attached adjusting means;

Figure 19 is a fragmentary section taken on line 19—19 of Figure 18, on an enlarged scale;

Figure 20 is a face view, partly broken away, of a horizontal tie bar;

Figure 21 is a face view, partly broken away, of a diagonal brace bar;

Figure 22 is a side elevation of a supporting post, partly broken away;

Figure 23 is a section, on line 23—23 of Figure 22;

Figure 24 is a section taken on line 24—24 of Figure 22;

Figure 25 is a side elevation of an extension leg for the post;

Figure 26 is a cross section on line 26—26 of Figure 25;

Figure 27 is a perspective view of a building section partly closed for shipment;

Figure 28 is a perspective view of the underside of a floor section;

Figure 29 is a section, on an enlarged scale and partly broken away, taken on line 29—29 of Figure 28, reversed to show the floor portion uppermost, and showing a fragmentary portion of an adjacent section; and

Figure 30 is a view similar to Figure 29, and reversed as in Figure 29, taken on line 30—30 of Figure 28.

Referring first to the form of construction shown in Figures 1, 2 and 3, our improved structure comprises the roof sections or panels 41

which have adjacent short or end edges hingedly connected together and girder sections 42 with their upper edges hingedly connected to the side edges of the panels and their meeting edges hinged together at 43 in the plane of the hinged connection between the roof sections. The gap at the ridge between the hinged roof sections is covered by a ridge strip 44. Posts 45 are detachably connected to the ends of the girders adjacent the roof section corners; these posts being provided with integral brace gussets 46. The posts are further provided with adjustable feet 47. The posts are connected by horizontal tie bars 48 and diagonal brace bars 50. The side walls are provided with hinged vent flaps 49. These several elements of the construction and their means and methods of assembly will be discussed in detail hereafter.

The individual roof panels 41 may be formed of any sufficiently strong and weather resisting material which is reasonably light in weight, such as plywood, compressed fibre board or sheet metal. In the drawings, Figure 4, they have been shown as comprising a smooth top sheet of metal 51 and a corrugated or rigidized sheet 52 under the top plate and contacting therewith at a multiplicity of points. As shown in Figures 4 and 5, the meeting hinge edges of the panels are housed in reversely bent sheet metal members 53 provided with hooked flanges 54 coating with packing strips 55 with the parts in the assembled position, and with the inturned edges 56 of the strip 44. As shown in Figures 8 and 17, the free outer edges of panels 41 are housed in reversely bent sheet members 57 having drip flanges 58.

The lateral edges of the panels are provided with the reversely bent housing members 59 and 60, respectively, as shown in Figure 16. Member 59 has an upturned hook flange 61 adapted to interlock with the downturned hook flange 64 on the housing member 60. The member 59 has the continuous raised bead 63 which not only stiffens the structure but acts to reduce any flow of water from the roof section into the space between sections. The upwardly inclined portion of hook flange 64 has a similar function. It will be noted, however, that the hook flange 61 serves as a gutter to carry off any water which does enter the space between sections. The housing member 60 has a lower stiffening bead 65 similar to the bead 63.

The form of hinged connection between roof sections at the ridge is shown in Figures 4 to 7, inclusive. The hinge comprises similar fixed members 67 secured at spaced points to the under side of the adjacent roof sections as by welding. An integral intermediate hinge member 68 is provided with an upstanding double flange portion 69, this member 68 being secured to the two fixed members 67 by the headed pins 70. The pins 70 are held in place by cotter pins 71 and have extended parallel ends 72. As best shown in Figure 4, the flange 69 fits up into the ridge strip 44 when the roof sections are folded for storage or shipment.

As shown in Figures 5 to 7, inclusive, the ridge strip 44 is held in place by a fixed tie bar 74 and a swinging tie bar 75. These tie bars 74 and 75 are located toward the lateral edges of each roof section as shown in Figure 6, a pair of bars to each room section. Each roof section has a separate ridge strip 44. The fixed tie bar 74 carries a coil spring 76, held in place on the tie bar by washer 77 and pin 78. The upper end of the spring engages the under face of the ad-

jacent hinge pins 72 to resiliently hold down the ridge strip. When the parts are folded for storage or shipment, the tie bars 74 and 75 assume the position shown in broken lines in Figure 4. 5 The swinging tie bar 75 carries the tubular handle 79 which houses spring 80, held in compression by pin 81 which extends through member 75 against the inturned upper edge flange of the handle 79. With the ridge strip 44 in its lower position, which is practically water and air tight, the parts are as shown in full lines in Figure 6 with the upper end of the handle 79 under the adjacent extended ends 72 of the hinge pins. When it is desired to open the strip 44 for ventilation, the tie bar 75 is swung out to the broken line position and raised to seat the pin 82 on the upper face of the hinge pin ends 72. The ridge strip sections 44 are offset at one end, as shown at 83 of Figure 6, so as to overlap an adjacent ridge strip when several units are set up end to end. When in the open position the ridge strips 44 are inclined upwardly, as indicated in broken lines at the left of Figure 6, the spring 76 being partially compressed and holding the strips 44 firmly in position.

One form of construction for securing the posts 45 to the roof girder 42 is shown in Figures 8 to 12, inclusive. The lower meeting edges of the girders 42 are connected by the hinges 84, shown in broken lines in Figure 2. The roof girders are connected to the lateral edges of the roof sections by hinges 85. One post 45 is designed to be secured to and support the girders of two adjacent sections, although the same post construction will engage and support a single girder at the end of a finished structure.

The upper end 86 of the post 45 is open and extends above the top of the knee brace gusset 46. The open end is wide enough to receive ends of two girders 42. The top of gusset 46 carries a horizontal flange 87, as best shown in Figure 9, on which the girder rests. The locking hooks 88 are hinged to the top of gusset 46 immediately below the flange 87, one being shown in packed position, in broken lines, and the other being shown in erected position, in full lines in Figure 8. The locking lever 89 is pivoted to the girder 42 at 90 and has a locking end 91 adapted to overlie the portion 92 of the hook 88. A slider 93 carries a spring 94 which holds a locking pin 95 in a slot in the member 89. The pin 95 is provided with a finger piece 96 by means of which it may be lifted against the resistance of the spring. When erected, the pin 95 fits in a selected opening of the series of openings 97 in the plate 98 secured to gusset 46. The assembled position of lever 89 is shown in broken lines in Figure 8.

Another form of construction for accomplishing this purpose is shown in Figures 13 to 15, inclusive. Here the post 45 is constructed in the same manner as in the prior construction and gusset 46 is also the same. The top of the gusset 46, however, carries a cap strip 101 having lateral flanges 102 to receive the girder webs and depending flanges 103 which embrace the top edge of the gusset 46. The swinging locking flaps 104 are pivoted at 105 below flanges 102. Each flap 104 carries a latch 106 pivoted to the flap at 107, the latch having a locking lug 108 normally urged to locking position by spring 109. Additional latch members 110 and 111 are pivoted to flanges 103 at points 112 and 113, respectively, as shown in Figure 13. These latches 110 and

111 are provided with springs 114 and 115 and finger pieces 116 and 117, respectively. The latches 110 and 111 hook over portions of flange 118 on the lower edge of the girder 42, this flange being shown in Figures 13 to 15 and being notched or cut away to receive the latches 110 and 111, as shown in Figure 13.

The post construction, and particularly the lower portion thereof, is shown in Figures 22 to 26, inclusive. The tubular leg 45 is provided with slots 120, as shown in Figures 22 and 23, to receive the transverse brace members 48, which will be described hereafter. It is also provided with holes 157 to receive the adjustable arms for raising the vent flaps or wall sections 49. The solid adjustable foot member 121 is fitted within the tubular post 45. Member 121 has an elongated foot or bearing portion 122 which is shown as having a hole 123 formed therein to receive a tent pin to secure the foot in place upon the ground. The slot 124 extends the major portion of the length of the foot member 122 and has the reversely directed racks 125 and 126 extending along the walls of its upper portion. The rocking ratchet member 127 is pivoted at 128 in a U-shaped member 134 carried by the adjusting screw 129. This screw is supported in a threaded block 130 secured to the post 45 by the pins 131. The finger piece 132 is connected to the ratchet member 127 so that it may be rocked to release its ratchet fingers from the racks. It will be understood that the foot member 121 is assembled with leg 45 by being slipped upwardly into it before the ratchet 127 and its supporting and manipulating parts are assembled upon the leg, these being assembled in the slot 124 and between the racks 125 and 126. The post 45 is also provided with the split stud 133 to receive the lower end of the diagonal brace member 50.

The transverse brace member 48 is shown in detail in Figure 20. The member is positioned at substantially the height of the slots 120 formed in post 45 and its ends are provided with hooks 135 and 136 adapted to fit in the slots. The slide guide 140 is secured to one end of member 48 adjacent the hook 135 and holds the slide 137 actuated by finger piece 138. This slide 137 is retracted when placing hook 135 into slot 120 and when thrust to the position of Figure 20, locks the hook in the slot. The end of slide 137 is sufficiently long so that it also locks in place the hook 136 of an adjacent member 48 when that is fitted into the same post. The diagonal brace, shown in detail in Figure 21 is permanently pivoted to member 48 at 139. As shown in Figure 21, member 50 is provided with a key hole slot 141 which is fitted over the split stud 133 on post 45. It is fitted over the stud before member 48 is moved to position, after which the diagonal position of member 50 prevents the slot from clearing the stud and retains the member in place.

The structure has been shown as provided with vent flaps or swinging upper wall members 49 at each side of the building section. These are shown in detail in Figures 18 and 19. The vent flaps comprise a rectangular body, preferably formed of metal, though they may be formed of any weather resistant sheet material. As shown in detail in Figure 19, the body has an upper, outwardly inclined section 144, with the edges bent inwardly and reversely bent, as shown at 145. The remainder of the edge of the flap is formed in a similar manner and the body of

the flap may be corrugated for stiffness, as indicated at 146 of Figure 18. The members 48 are provided at each side with pivoted supporting brackets 147, connected to the body by hinges 148 in such manner that they may be swung at right angles to the member when in use or parallel with the member for storage or shipment. The hinge 148 has the spring 149 fitted on the hinge pin to frictionally hold the bracket in the position on pivot pin 151 to which it may be moved. The bracket 147 has the hole 150 formed therein to fit over the pivot pin 151 on the fixed bracket 152 carried by the post 45.

The vent flap 49 is provided at each end with a supporting arm 153, pivotedly secured to the rear face of the flap at 154. These arms 153 are provided with spaced lugs 155 and 156 adapted to fit in any one of holes 157 in the post 45 to maintain the vent flap in opened or ventilating positions.

The units may be folded into a book for shipment with the posts 45 and vent flaps 49 contained therein. A partially closed unit is shown in perspective in Figure 27. The girder members 42 fold inwardly against the inner face of the roof sections, as shown in the drawing. The roof posts 45 are placed within the roof sections as are the vent flaps 49. The diagonal braces 50 are folded parallel to the transverse braces 48 and the brace assembly for each bay may be slipped into the tubular post through its upper end. A covering for the lower wall portion, formed of canvas or other flexible material, may be folded and placed within the book at the space indicated by 160 in Figure 27.

Thus, it will be seen that each unit is fully self contained and forms a compact assembly for shipment and storage. It will be understood that two additional posts are needed to complete a building structure, and these may be packed separately. If the ends of the building are to be closed, these end closures must be shipped separately. These may be of canvas or other flexible material and may be secured in place in any desired manner. For example, they may be hooked in holes 180 provided in girder members at the ends of the structure.

In some cases, it may be desired to provide a floor for the building structure, and we have shown such a floor in Figures 28 to 30, inclusive. This floor is designed so that two floor sections fully cover the area of a single sectional unit of the building. These two floor sections are so constructed that they form a case or box to enclose the building unit for shipment or storage.

The floor surface 161 preferably comprises a single sheet of material such as plywood or dense fibre board, though it may be formed of metal or other material if desired. The floor surface 161 is bound and supported by side members 162 and 163 and end members 164 and 165 and is further supported by V-shaped cross braces 166. The side member 162 of N-shaped, having a downwardly extending flange 167 and a V-shaped rib 168. The side member 163 is of the full depth of the floor support and has a V groove 169 to receive the V rim 168 of the adjacent section when floor sections are placed parallel, as shown in Figure 30. The member 163 also has a flat ground engaging flange 170. This flange also serves to hold a facing unit in place when the floor sections are used to enclose a book or building unit for shipment or storage. This is indi-

cated in broken lines in Figure 30, the building structure book being indicated at 171.

The end member 164 is generally channel shaped, as shown in Figure 29, with a ground engaging flange 172. This flange 172 also serves to enclose the opposite end member 165 of the associated floor section and particularly the flange 173 when the parts are assembled for storage or shipment. The web of member 165 is provided with a tongue 174 extending half its length and a groove 175 extending for the remainder of its length to form an interlock when the floor sections are placed end to end. Thus, all floor sections are interlocking and mutually supporting to form a continuous and smooth floor.

While we have shown certain preferred embodiments of our invention, they are to be understood to be illustrative only, as it is capable of variation and change to meet differing conditions and requirements, and we contemplate such modifications as come within the spirit and scope of the appended claims.

We claim:

1. In a collapsible building structure, a pair of roof sections hingedly connected together at an end of each section, and a roof girder structure hingedly connected to a lateral edge of the connected roof sections, said girder structure comprising two sections, one hinged to each roof section, said girder sections being hingedly connected together in substantially the same plane as the roof sections whereby the girder sections may be folded against the under face of the roof sections as the roof sections are folded together, the hinge serving as a connector under tension when the members are in erected position.

2. In a collapsible building structure, a pair of roof sections hingedly connected together at an end of each section, the hinged connection providing a space between the sections, a separate ridge member and adjustable resilient securing means for said member, said securing means being connected to the ridge member and selectively engaging the roof hinge structure to draw the ridge resiliently against the roof or support the ridge clear of the roof.

3. In a collapsible building structure, roof sections foldable together to form a flat book, girder sections hinged to the roof sections adjacent their lateral edges and foldable inwardly between said sections, and detachable posts for supporting the roof sections, said posts fitting within the folded roof sections between the girder sections for shipment.

4. In a collapsible building structure, roof sections foldable together to form a flat book, girder sections hinged to the roof sections adjacent their lateral edges and foldable inwardly between said sections, detachable wall sections and detachable posts for supporting the roof sections, said wall sections and posts fitting within the folded roof sections between the girder sections for shipment.
